FIG. 1

FIG. 2

INVENTOR:
Zamora C. Cauffman

By
C. D. Staskins

ATTORNEY

UNITED STATES PATENT OFFICE.

ZAMORA C. CAUFFMAN, OF SEATTLE, WASHINGTON.

CHIN-SUPPORTER.

1,247,222.

Specification of Letters Patent. Patented Nov. 20, 1917.

Application filed December 20, 1916. Serial No. 138,113.

To all whom it may concern:

Be it known that I, ZAMORA C. CAUFFMAN, citizen of the United States, residing at Seattle, in the county of King and State 5 of Washington, have invented a certain new and useful Improvement in Chin-Supporters, of which the following is a specification.

My invention relates to improvements in 10 chin supporters, and the object of my invention is to provide a chin supporter which, by its form of construction and by the character of the material of which it is made, shall be adapted smoothly to fit and cover 15 the surface of the chin and portions of the lower jaw of any child or grown person, and to be so bound to the head that such person's lower jaw may be maintained in a position to keep the mouth closed while 20 such person sleeps, thus to prevent such person from snoring, and to hold the relaxed muscles of the cheeks and lower portion of the face in their natural positions thereby to preserve the youthful contour of the under 25 portion of the cheeks and chin.

A further object of my invention is to provide a chin supporter which shall embody two pairs of fastening strings and associated devices that shall so conjointly act, in 30 the operation of applying the chin supporter, that a tightening strain on either of said pairs of strings shall impart an equal tightening strain on the other pair thereof thus more nearly to equalize the strain on 35 all parts of the supporter.

I accomplish these objects by devices illustrated in the accompanying drawings, wherein Figure 1 is a view in side elevation of a person's head to which is fastened 40 a chin supporter embodying my invention; and Fig. 2 is a plan view on a reduced scale of the same chin supporter as it appears when not in use.

Referring to the drawings, throughout 45 which like reference numerals designate like parts, a textile fabric 3 that is loosely woven, or knitted, to adapt it smoothly to conform to an irregular surface by reason of its elasticity, is formed to be oblong, one 50 of its side edges being straight and the opposite one thereof being outwardly curved while each of its opposite end portions is bifurcated, to form terminals 4 and 5 and terminals 6 and 7, as shown in Fig. 2.

55 The fabric 3 is bordered throughout all its edges by a binding 8 of tape.

Securely fastened to the terminals 4 and 5 is a pair of strings, as strings 9 and 10; and likewise fastened to the terminals 6 and 7 is a similar pair of strings, as strings 11 60 and 12, the strings of each pair being long enough to be tied by a bow knot, as bow knots 15 and 16, when they are extended from the fabric 3 to meet over one's head as shown in Fig. 1. 65

A metal loop connector 13 having two integral eyelets 14 is disposed to be adjustably movable on each of the strings 9 and 10 as indicated in Fig. 2, the loop portions of said connectors 13 being extended toward 70 the strings 11 and 12 respectively.

To support one's chin the fabric 3 is placed symmetrically with the outwardly bowed side edge adjacent to the mouth and with the opposite straight side edge 75 under the chin adjacent to the neck, thereupon the strings 11 and 12 are tightly drawn backwardly to cross each other behind the neck, the string 12 then being extended upwardly on the right hand 80 side of the head to a point above the right ear where it is projected through the loop of the loop connector 13 of the string 9 to extend thence to the top of the back part of the head, there to be tied by a bow knot 85 to the end of the string 11 which extends downwardly on the left hand side of the head to a point above the left ear where it passes through the loop of the loop connector 13 of the string 10 and thence downwardly and around the back of the neck to the terminal 6 of the fabric 3. 90

The loop connector 13, through whose eyelets 14 extend the respective strings 9 and 10, are adjusted so that when said 95 strings 9 and 10 are extended to the more forward portion of the top of the head and there tied by a bow knot 15, then said loop connectors 13 will be disposed at points higher than the tops of the ears. 100

With the strings so relatively disposed it is manifest that in the operation of tying the knots 15 and 16 one-half of the strain exerted on the pair of strings last tied will be imparted to the other pair that was first 105 tied, whereby all of the terminals 4, 5, 6 and 7 will be subjected to equal strains thereby to cause the loosely woven fabric 3 smoothly to conform to the contour of the surface covered by it. 110

Manifestly, the shape of the piece of fabric 3 may widely differ from its shape

as shown in the drawings, and the loop connectors 13 may be movably disposed on either of the pairs of strings and may be different in form and material, without departing from the spirit of my invention.

What I claim is:

1. A chin supporter comprising an elongated band, said band having a string attached to each end thereof adjacent one longitudinal edge, a loop-like connector adjustably attached to each of said strings, a second string attached to each end of said band adjacent the other edge thereof, said first-named strings being adapted to be tied at a point near the forward part of the head of the user and arranged with their loop-like connectors extending rearwardly and said second-named strings being adapt-

ed to be crossed at the back of the neck of the user and slidably received by said connectors and tied at a point near the back part of the head of the user.

2. A chin supporter comprising an elongated band, a pair of securing strings secured to each end of said band, and means whereby a tightening strain on two of said strings will impart an equal tightening strain on the other two of said strings.

In witness whereof, I hereunto subscribe my name this 9th day of December, A. D., 1916.

ZAMORA C. CAUFFMAN.

Witnesses:

FRANK WARREN,
GEO. BLAIR.
